(57) **CLAIM**

The ornamental design for a rocket shaped stylus, as shown and described.

DESCRIPTION

FIG. 1 is a perspective view of a rocket shaped stylus showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken line showing portions of the rocket shaped stylus is included for the purpose of illustrating unclaimed portions and forms no part of the claimed design.
